RAVEL STOP FOR KNITTED FABRICS AND
METHOD OF MAKING THE SAME

Otto F. Smetana, Concord, N. C.

Application July 8, 1941, Serial No. 401,438

12 Claims. (Cl. 66—172)

This invention relates to ravel stops for knitted fabrics such as stockings and the like, and also to the methods for producing such stops.

Various means have heretofore been proposed to prevent raveling in knitted fabrics, particularly hosiery, including courses in which loops of alternate wales were laterally transferred and doubled with loops of the intervening wales as instanced in the formation of transverse picot rows or courses. While such barriers do stop raveling in one direction, they are not positive in preventing raveling beyond them in the opposite direction. For example, in a fashioned stocking which is made from a blank knitted from the welt top to the toe and having a row of picot stitches between the toe and the instep, a rupture occurring in the instep or leg will be stopped at the picot course, whereas a rupture originating in the toe will run upward past the picot row and continue through the instep and leg.

The object of my invention is to overcome the above drawback. In other words, I aim to provide a ravel stop which will operate as a barrier to prevent runs from continuing through it irrespective of the side of the barrier in which the runs may originate. This objective I attain as hereinafter more fully disclosed by producing transversely of the fabric, during the knitting of the stocking blank, one or more rows of picot stitches, and afterwards forming a line of elastic stitches crosswise of the fabric from a separate thread or threads in such manner as to effectively lock the picot stitches.

In the drawing, Fig. 1 shows, in side elevation, a stocking with a ravel stop between its toe and instep, conveniently embodying my invention.

Fig. 2 is a diagrammatic view showing a fragment of the stocking fabric within the area of the dotted rectangle II in Fig. 1.

Fig. 3 is a view corresponding to Fig. 2 before the application of the lock stitching.

Fig. 4 is a fragmentary view showing how the stocking fabric is impaled upon the points of a looping machine for the formation of the lock stitching; and

Figs. 5 and 6 are views corresponding to Figs. 2 and 3, showing an alternative embodiment of my invention.

The stocking shown in Fig. 1 is intended to represent one formed from a flat plain-knitted blank and seamed down the back as is common in the production of full fashioned hosiery, the leg 1 being suitably shaped, and the foot 2 likewise fashioned in any approved manner and the latter at the same time reinforced as indicated by

the line shading. To form the ravel stop shown in Fig. 2, I produce from the knitting thread or threads at or near the juncture between the instep and toe during the knitting of the blank for the stocking, two closely adjacent transverse rows 3, 4 of laterally transferred picot stitches (see Fig. 3), with incidental formation of transverse lines of holes or interstices 3a, 4a, the loop transferring being effected so that said holes or interstices 3a, 4a of the two rows are disaligned or staggered relative to each other and with respect to the direction of the wales of the fabric.

I thereupon fold the blank along a line A—A in Fig. 3 medially between the picot rows 3, 4, and at the same time bring corresponding holes or interstices 3a, 4a of said rows into superimposition or alignment. With this accomplished, I run the fabric on to the points P of an ordinary looping machine such as diagrammatically shown in Fig. 20 4 by impaling the corresponding pairs 3a, 4a of the picot holes or interstices upon alternate points, the intermediate doubled loops of the picot rows being at the same time impaled upon the intervening points of said machine. The looping machine may be of a type having a needle N and a looper L each of which carries its individual thread, the needle thread being designated T and the looper thread T'. By the operation of the looping machine and due to the mounting of the fabric in the way above explained, loops 5 of the needle thread are passed through the registering openings 3a, 4a on the alternate points as well as through the registering intervening 25 points of the machine with resultant formation of a crosswise line of stitches in which the needle thread loops 5 are connected at one face of the fabric as shown in Fig. 2 by looper thread loops 6. As a consequence of this procedure it will be evident that an effective chain stitch barrier is formed which will operate to stop runs in the fabric irrespective of the side of origin of such runs, while allowing free expansion and contraction of the fabric when the stocking is worn. 30 Preferably, the barrier is made to extend only across the top of the stocking toe as shown in Fig. 1, i. e., between the lines which form the inner limits of the reinforcements of the foot sides for protection of the sheer instep portion of the stocking. However, if desired, it may be made to extend entirely around the toe.

It is of course to be understood that within the scope of my invention as defined in the appended claims, similar run stops may be formed at other points in the stocking, for example along

the juncture of the welt top 7 and the leg portion 1. It is to be further understood that my invention is not limited to the use of supplemental lock stitches formed from two threads as herein illustrated by way of example, since perfectly satisfactory locking seams may be produced from either a single thread or with threads in excess of two if this should be found more convenient or desirable in practice, providing that the elasticity of the fabric is not restricted. It is also to be understood that the lock stitching may be formed otherwise than upon a looping machine without departing from the spirit of my invention, and that, if desired, other picot rows may be run in between the rows 3 and 4.

The alternative embodiment of my invention shown in Figs. 5 and 6 involves the use of but a single row 3x of picot stitches, and in forming the ravel stop the fabric is applied to the looping machine with the doubled loop pairs of the picot row impaled on the points P of said machine as instanced in Fig. 6. After the operation of the looping machine upon the impaled fabric the ravel stop will appear as shown in Fig. 5 with the loops 5x of the needle thread penetrating the doubled loops of the picot from one side of the fabric, and with loops 6x the looper thread connecting said needle thread loops at the opposite side of the fabric.

Having thus described my invention, I claim:

1. A ravel stop for knitted fabrics comprising a row of picot stitches which are formed from the thread used in the knitting; and a chain of stitches formed from a separate thread or threads along the picot row with the stitches of said chains respectively locking the stitches of the picot.

2. A ravel stop for knitted fabrics comprising at least two contiguous transverse rows of picot stitches which are formed from the thread used in the knitting; and interconnected lock stitches formed from a separate thread or threads each such lock stitch passing through a crosswise aligned pair of aligned holes or interstices of the two rows of picot stitches.

3. A ravel stop for knitted fabrics according to claim 2, wherein the holes or interstices of the two picot rows are offset or staggered somewhat relative to each other in the direction of the fabric wales.

4. A ravel stop for knitted fabrics comprising at least two contiguous transverse rows of picot stitches which are formed from the thread used in the knitting; and a transverse line of chain stitches formed from a separate thread or threads with the stitches of such line extending respectively through crosswise aligned pairs of holes or interstices of the two picot rows.

5. A ravel stop for knitted fabrics according to claim 4, in which the holes or interstices of the two picot rows are offset or staggered somewhat relative to each other in the direction of the fabric wales.

6. In a knitted stocking, a ravel stop extending transversely of the same, said stop comprising at least two contiguous transverse rows of picot stitches and being formed from the thread used in the knitting; and interconnected elastic locking stitches formed from a separate thread or threads, said locking stitches respectively passing through crosswise aligned pairs of holes or interstices of the two picot courses.

7. A ravel stop according to claim 6, in which the holes or interstices of the two picot rows are offset or staggered somewhat relative to each other in the direction of the fabric wales.

8. A ravel stop according to claim 6, which is located crosswise of the toe portion of the stocking.

9. The method of producing a ravel stop in knitted fabrics which comprises forming, during the knitting of the fabric from a thread or threads at least two contiguous transverse rows of laterally-transferred picot stitches; and forming a line of interconnecting lock stitches from a separate thread or threads, with the lock stitches of said line passing respectively through crosswise aligned pairs of holes or interstices of the two picot rows.

10. The method of producing a ravel stop in knitted fabrics which comprises forming, during the knitting of the fabric from a thread or threads at least two contiguous transverse rows of laterally-transferred picot stitches, with the holes or interstices of said rows offset or staggered relative to each other in the direction of the fabric wales; and forming a line of interconnecting lock stitches from a separate thread or threads with the lock stitches passing respectively through crosswise aligned pairs of holes or interstices of the two picot rows.

11. The method of producing a ravel stop in knitted fabrics which comprises forming, during the knitting of the fabric from a thread or threads, a transverse row of laterally-transferred picot stitches; impaling the stitches of the picot row upon a series of points; and forming a line of interconnected lock stitches from a separate thread or threads along the picot row and causing said lock stitches to interlock respectively with the picot stitches.

12. The method of producing a ravel stop in knitted fabrics which comprises forming, during the knitting of the fabric from a thread or threads, at least two contiguous transverse rows of laterally-transferred picot stitches; folding the fabric along a transverse line medially between the two picot rows to bring corresponding pairs of stitches of the picot rows into superimposition; and then forming a line of interconnecting stitches from a separate thread or threads along the picot row and causing the stitches of such line to interlock respectively with corresponding pairs of the superposed picot stitches.

OTTO F. SMETANA.
